UNITED STATES PATENT OFFICE

JOHN R. BOUTELL, OF MILWAUKEE, WISCONSIN

CONTACT MAKING AND BREAKING DEVICE

Application filed August 3, 1925. Serial No. 47,795.

It is an object of this invention to provide an improved and simplified form of contact making and breaking device capable of handling heavy currents such as used in spot welding and the like machines.

Another object of this invention resides in the provision of a device of the character described which will be very efficient in construction and which will quickly make and 10 break the circuit to substantially eliminate destructive arcing forces.

And a still further object of this invention resides in the provision of an improved and simplified contact making and breaking device which may be mounted on a spot welding or the like machine to be conveniently 15 operated from a treadle or other operating member.

With the above and other objects in view 20 which will appear as the description proceeds, my invention resides in the novel construction, combination and arrangement of parts substantially as hereinafter described and more particularly defined by the appended 25 claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a side view, partly in section and partly in elevation, illustrating a contact making and breaking device embodying my invention, and

Figure 2 is a view, partly in section and 40 partly in elevation, taken through Figure 1 on the plane of the line 2—2.

Referring now more particularly to the accompanying drawing, in which like numerals designate like parts throughout the 45 several views, the numeral 5 designates a

housing or casing, one side of which is open and adapted to be normally closed by a removable cover 6 secured in position by a screw or other fastenings 7. Journaled in the housing on a shaft 8 is a rotatable actuator 9 of disc shape having a segmental portion thereof cut away to provide a recess 10 in which the free end 11 of a movable contact carrying lever 12 rides. The end walls 13 and 14 of the recess 10 form impact surfaces adapted to strike the free end 11 of the movable contact carrying member, in the manner hereinafter described to engage and disengage a movable contact 15 fixed to the member 12 by a screw or other fastening member 16 with a stationary contact 17.

The movable contact 15 has a socket terminal 18 electrically connected therewith to receive one end of a conductor 19 included in the circuit the device is adapted to control and the conductor 20 of the circuit is electrically connected with the stationary contact by a socket terminal 21 electrically connected therewith. The lever 12 is of insulating material such as fibre, bakelite, or the like, and its end portion 22 is pivoted on a shaft 23 mounted in the housing, a stop 12' being provided to limit opening movement of the lever. The stationary contact is insulated from the housing by a base 24 of insulating material to which it is removably secured by a screw or other mounting 25.

Extended into the housing through a slot or opening 26 in one end wall thereof is an actuating lever 27 of approximately angular shape which is journally mounted adjacent its apex on a shaft 28 mounted in the housing. The end portion 29 of the actuating lever disposed in the housing is operatively connected with the actuator 9 in the manner to be hereinafter described and the outer end or arm 30 thereof is connected with a treadle or operating member, not shown, through the medium of an operating rod or link 31 which is pivotally connected therewith, as at 32.

Fixed to the movable contact carrying lever 12 outwardly of its pivot 23 is an arm 33 to which one end of a substantially V-shaped spring 34 is pivotally connected, as at 35, the other end of the spring being connected with the shaft 28 preferably by being coiled therearound, as at 36. The spring 34 is constantly under compression and its point of pivotal connection with the lever 33 is so disposed that when the contact carrying member 12 is in full open position, the pivot point 35 is to one side of an imaginary line drawn through the axes of the shafts 23 and 28 and when the member 12 is in contact making position the point 35 is to the other side of the line so that the spring 34 yieldably retains the movable contact in either of its two positions.

The extreme inner end portion 29 of the actuating lever is enlarged and notched or recessed, as at 37, to receive an actuating pin 38 concentrically carried by the actuator 9, so that a pull on the link 31 to raise the end 29 of the actuating lever, causes the stud 38 to be moved in a clockwise direction with reference to Figure 1 turning the actuator on its pivot in a corresponding direction. This rotation of the actuator stores energy within an approximately V-shaped spring 39 having a coil 40 formed at its apex and having one end pivotally connected with a stud 41 concentrically carried by the actuator and its other end connected with a stud or rod 42 mounted in the housing substantially directly above the shaft 8.

The stud 42 is so arranged that as the actuator is rotated in a clockwise direction in the manner described, energy is stored within the spring 39, the ends of which are compressed by reason of the stud 41 moving toward the rod 42. As the stud 41 passes an imaginary line drawn through the stud 42 and shaft 8, the energy stored in the spring releases, causing the impact surface 13 to strike the free end 11 of the member 12 with a hammer blow, moving it against the force of the spring 34, the end of which passes beyond the dead center before the contacts are made to thus assist the force of the spring 39 in making a quick contact.

The parts are then in the positions illustrated by dotted lines in Figure 1 and the outer end portion 30 of the actuating lever is depressed so that an upward movement of the link 31 causes the other end of the notch or recess 37 to engage the stud 38 and rotate the actuator in a counter-clockwise direction. Energy is again stored within the spring 39 until the stud 41 passes the imaginary line drawn through the shafts 8 and 42 when the energy stored within the spring 39 is released causing the impact surface 14 to strike the free end of the member 12 and quickly separate the contacts 15 and 17, the point of engagement of the spring with the arm 33

soon passing dead center so that the spring 34 assists in the opening movement.

The spring 34 being under tension while the contacts 15 and 17 are made, prevents jumping apart of the contacts due to vibrations of the machine to which the contact making and breaking device is attached. The end portion 29 of the actuating lever is slotted, as at 43, to receive the adjacent end of the shaft 8, which passes therethrough to be journaled in the adjacent side of the housing.

From the foregoing description taken in connection with the accompanying drawing it will be readily apparent to those skilled in the art to which an invention of this character appertains that I provide a very simple and efficient switch construction which will produce a quick make and break in the circuit and one in which the contacts are spring held in either open or closed position to prevent their separation when in circuit making position by vibrations of the machine to which the device is attached.

I claim:

1. A device of the character described, comprising a stationary contact, a movable contact engageable with the stationary contact to make an electric circuit, means for yieldably retaining the movable contact in either circuit making or breaking position, substantially disc shaped actuating member having a cut-away portion to provide two impact surfaces, one impact surface being engageable with the movable contact when in circuit breaking position to move the same against its yielding means to circuit making position and the other impact surface being engageable with the movable contact when in circuit making position to move the same against its yielding means to circuit breaking position, and means operable by the rotation of said member to store energy within itself which is released prior to the engagement of an impact surface with the movable contact to thus strike the movable contact a blow sufficient to cause its quick movement.

2. A device of the character described, comprising a support, a lever pivotally secured to the support, a contact carried by the lever, a second contact carried by the support and with which the first contact is engageable to make an electric circuit, an arm connected with the lever, a substantially V-shaped spring having one end connected with said lever arm and the other end with the support, the point of connection between the spring and arm moving to opposite sides of an imaginary line drawn through the lever pivot and the point of connection of the spring with the support as the lever moves to either of its two limits, whereby the spring yieldably retains the lever in either of its two positions, and a rotatable actuator having a recess in which the free end of the lever ex-

tends so that rotation of the actuator in one direction causes one end wall of its recess to engage the lever and move it to contact making position and rotation of the actuator in a reverse direction causes the other end wall of the recess to engage the free end of the lever and move it to circuit breaking position.

3. A device of the character described, comprising a support, a lever pivotally secured to the support, a contact carried by the lever, a second contact carried by the support and with which the first contact is engageable to make an electrical circuit, an arm connected with the lever, a substantially V-shaped spring having one end connected with said lever arm and the other end with the support, the point of connection between the spring and arm moving to opposite sides of an imaginary line drawn through the lever pivot and the point of connection of the spring with the support as the lever moves to either of its two limits, whereby the spring yieldably retains the lever in either of its two positions, a rotatable actuator having a recess in which the free end of the lever extends so that rotation of the actuator in one direction causes one end wall of its recess to engage the lever and move it to contact making position and rotation of the actuator in a reverse direction causes the other end wall of the recess to engage the free end of the lever and move it to circuit breaking position, means for rotating the actuator, and a spring connected with the actuator and adapted to have energy stored therein during the first portion of the rotation of the actuator in either direction, the energy being released upon movement of the actuator through a predetermined degree to cause the same to strike the lever with a blow.

4. A device of the character described, comprising a stationary contact, a movable contact engageable with the stationary contact to close an electric circuit, means for yieldably retaining the movable contact in either closed or open position, a substantially disc shaped actuating member rotatably mounted and having a segmental portion cut away to provide two impact surfaces, one impact surface being engageable with the movable contact when in circuit opening position to move the same against its yieldable retaining means to circuit closing position and the other impact surface being engageable with the movable contact when in circuit closing position to move the same against its yieldable retaining means to circuit opening position, spring means for yieldably retaining the actuating member in either of its positions, a stud carried by the actuating member, an operating lever, means pivotally mounting the operating lever, said operating lever having an arcuate recess in which the actuating member carried stud is posi-

tioned whereby movement of the operating lever causes rotation of the actuating member, and means whereby rotation of the actuating member compresses its yieldable retaining means to store energy therein which energy is released after a predetermined degree of rotation to snap the actuating member to its opposite limit of movement and with it the movable contact.

In testimony whereof I affix my signature. 75
JOHN R. BOUTELL.
